UNITED STATES PATENT OFFICE

2,209,962

LASTING MACHINE

René E. Duplessis, Beverly, Mass., assignor to
 United Shoe Machinery Corporation, Borough
 of Flemington, N. J., a corporation of New
 Jersey

Application August 15, 1938, Serial No. 224,937
 Renewed August 5, 1939

38 Claims. (Cl. 12—14)

This invention relates to lasting machines, and is herein illustrated as applied to a bed-lasting machine constructed generally as disclosed in United States Letters Patent No. 1,284,870, granted on November 12, 1918 upon an application of Matthias Brock, but modified in certain respects as further disclosed in Letters Patent No. 1,495,169, granted on May 27, 1924 on an application of Joseph Fausse and René E. Duplessis.

It is to be understood, however, that in various novel and useful aspects the invention is not limited to machines of the illustrated type. It is also to be understood that while the invention is herein illustrated and described with reference to operations performed on the toe end of a shoe, it is not thus limited in its applicability.

In one aspect, the invention has in view the provision in a lasting machine of means for conveniently and effectively applying heat to the portion of the shoe operated upon by the lasting means. It is contemplated that heat may thus be applied for any purpose for which it may be advantageous to use it, the present disclosure illustrating its use for the purpose of softening or activating thermoplastic cement previously applied to the insole for securing the margin of the upper in lasted position. In accordance also with the illustrative disclosure, the heat is applied not only to cement on the insole, but also to the margin of the upper which is to engage the cement, to afford better insurance that the cement will effectively adhere to the upper. For the purposes in view the machine is provided with a heated member which engages the cement on the insole and also engages the margin of the upper as the latter is wiped inwardly over the insole by the lasting wipers characteristic of machines of the illustrated type. The invention provides novel means for supporting and controlling this member, the construction shown comprising a novel arrangement of swinging arms whereby the operator may conveniently move the member from an initial retracted position to a position over the shoe and may also move it heightwise of the shoe into contact therewith. While the member may be heated in different ways within the scope of the invention, the machine herein shown is conveniently provided with a heater on which the member rests in its retracted position and away from which it is carried when it is to be applied to the shoe. The above-mentioned arms comprise a manually operated arm arranged to extend generally lengthwise of the shoe and to be swung downwardly to press the heating member on the shoe, and another arm on which that arm

is supported, this other arm being arranged to extend normally heightwise of the shoe but mounted to swing lengthwise of the shoe in a downward direction against the resistance of a return spring in response to a pull of the manually operated arm thereon to permit the heating member to be carried by the latter arm to a position over the shoe. To render the manually operated arm more effective as a lever in pressing the member on the shoe, a device is provided for locking the other arm against return movement. The heating member, in the construction shown, is mounted on one end of a bar which extends lengthwise of the shoe and which is suspended by a link on the above-mentioned manually operated arm, the other end of this bar being connected by a link to still another arm mounted to swing lengthwise of the shoe in a downward direction as the member is carried to its position over the shoe. To permit the member to be positioned more accurately in proper relation to the shoe and to be moved outwardly over the wipers while in contact with the margin of the upper, provision is afforded for moving it at the will of the operator lengthwise of the manually operated arm, this arm having mounted thereon a hand lever by bodily movement of which the arm itself is operated and by swinging movement of which the above-mentioned bar may be moved lengthwise relatively to the arm.

In accordance with a further object of the invention the above-mentioned heating member, under control of the mechanism above described, may be and is herein illustrated as also used to press the margin of the upper against the wipers to render the wipers more effective to wipe the margin tightly over the insole and to assist in preventing the formation of objectionable wrinkles therein, the member thus performing the function of what is commonly termed a retarder. It is to be understood, moreover, that the member may, if desired, be used for this purpose alone, in which case it may or may not be heated, the mechanism provided for controlling and operating it being as useful and effective when the member performs this function as when it serves for heating purposes in the manner hereinbefore described.

The novel features of the invention, including various novel details of construction and combinations of parts, will now be more particularly described with reference to the accompanying drawings and thereafter pointed out in the claims.

In the drawings,

Fig. 1 is a view in front elevation of a portion

55

of a machine in which the invention is embodied, with parts of the structure broken away and with a shoe in position for the lasting operation;

Fig. 2 is a plan view of the portion of the machine shown in Fig. 1;

Fig. 3 is a view in rear elevation, on an enlarged scale, of structure provided for purposes of the present invention, with parts broken away;

Fig. 4 is a view similar to Fig. 1, on a larger scale, of a portion of the structure there shown, but with the parts in the positions which they occupy when the heating member is in contact with the insole, certain parts being shown in section;

Fig. 5 is a plan view showing the heating member in contact with the insole as in Fig. 4;

Fig. 6 is a vertical section showing the heating member in use as a retarder in contact with the margin of the upper over the wipers;

Fig. 7 is a section on the line VII—VII of Fig. 6; and

Fig. 8 is an inverted plan view of the heating member detached.

In view of the disclosure of features of the general organization of machines of the illustrated type in the above-mentioned Letters Patent, the drawings show only as much of such a machine as is necessary for an understanding of the invention, and such parts as are common to prior machines of this type will be only briefly herein-after described. The shoe is supported bottom upward in position for the lasting operation on a post 2 provided with a pin 4 which enters the usual spindle hole in the heel end of the last and on a toe rest 6 (Fig. 4) mounted on another post 8. The shoe is clamped about its heel end by a heel band 10, and this end of the shoe may, if desired, be lasted in the usual manner, the margin of the upper being wiped inwardly over the insole by the use of heel wipers 12. For lasting the toe end of the shoe there are provided toe wipers 14 which embrace the upper about the toe and are operated by a hand lever 16 to wipe the margin of the upper inwardly over the insole, the wipers as usual receiving advancing movement lengthwise of the shoe and closing movements laterally of the shoe. The toe wipers are supported by means which may be tipped in different directions to adjust the wipers relatively to the shoe by the use of mechanisms which need not be herein described, these mechanisms and the wipers, together with the hand lever 16 and the means connecting it to the wipers, being all supported on a vertically movable slide 18 connected by a link 20 to a double-acting treadle 22. By means of this treadle, therefore, the wipers may be moved upwardly to wipe the upper heightwise of the last before wiping its margin inwardly over the insole and may be thereafter lowered to press the margin of the upper down on the insole. The machine herein shown is also provided with a toe band 24 controlled by the hand lever 16 for clamping the upper against the end and side faces of the last to assist in the lasting operation, such a toe band, however, being frequently omitted in machines of the illustrated type.

As thus far described, the machine herein shown is constructed as heretofore. For purposes of this invention a cover plate used heretofore over the toe wipers 14 is replaced by a different cover plate 26 formed integral with which is a bracket 28 arranged to extend lengthwise of the shoe. Pivotedly mounted respectively on pins 30 and 32 (Fig. 3) on the bracket 28 are a pair of

arms 34 and 36 spaced apart lengthwise of the shoe and arranged to extend normally heightwise of the shoe. Controlled in certain respects by these arms is a bar 38 extending generally lengthwise of the shoe, this bar having mounted on one end thereof, as more particularly hereinafter described, a plate 40 which is used to apply heat to cement on the toe end of the insole and also to the margin of the toe end of the upper and is further used to press the margin of the upper on the wipers in the toe-lasting operation. At its other end the bar 38 is connected by a link 42 to the arm 36 so that the bar may at times be moved lengthwise relatively to this arm. This link is held normally, however, in a relation to the arm 36 determined by engagement of a shoulder 44 on the link with a corresponding shoulder 46 on the arm. For this purpose a pin 46 is mounted in a socket in the arm with its outer end in contact with the link, the pin being urged outwardly by a spring 48 in the arm engaging a head on the inner end of the pin. In a location between its opposite ends the bar 38 is suspended by a link 50, bifurcated at its upper and lower ends, on a manually operated arm 52 which extends generally lengthwise of the shoe, this arm being bifurcated at one end and pivotally connected at that end by a pin 54 to the upper bifurcated end of the arm 34. Pivotally mounted between its opposite ends on a pin 56 carried by the arm 52 is a hand lever 58 provided with a handle 60, the lower end of this hand lever being connected by a link 62 to the same pin 64 which connects the bar 38 to the lower end of the link 50. By bodily movement of the hand lever 58, therefore, the arm 52 may be swung upwardly and downwardly about the pin 54 and may also be moved lengthwise, and by swinging movement of the hand lever about the pin 56 the bar 38 may be moved lengthwise relatively to the arm 52.

The arm 34 normally occupies a substantially vertical position, as shown in Figs. 1, 2 and 3, determined by engagement of a depending tail portion 66 thereof with a pin 68 on the bracket 28. The arm is held in this position by a spring 70 connected to its tail portion and to a pin 72 on the cover plate 26. This serves to position the plate 40 over a heater 74 on which it rests under the influence of gravity, the heater consisting of a plate fastened to the cover plate 26 and having therein a recess in which is mounted an electrical heating unit 76 for maintaining it in a heated condition. A shield 78 covered on the top with asbestos 80 guards against contact of the operator's hand with the heater.

When the operator standing in front of the machine wishes to use the plate 40, which may be after he has raised the wipers by the treadle 22 to wipe the upper upwardly to the edge of the insole but before he has moved the hand lever 16 far enough to begin to wipe the margin of the upper inwardly over the insole, he takes hold of the handle 60 with his right hand and moves the arm 52 lengthwise to carry the plate from over the heater 74 to a position over the toe end of the insole which may have a coating of thermoplastic cement 82 (Fig. 5) in a hardened condition on its exposed face. At the beginning of this operation he may also swing the arm 52 upwardly enough to lift the plate from the heater. As the arm 52 is moved lengthwise its pull on the arm 34 causes the latter to swing toward the shoe in a downward direction against the resistance of the spring 70, and at the same

time the arm 36 is swung similarly to the arm 34 by the pull of the bar 38 thereon. This bar, as above explained, may be moved lengthwise relatively to the arm 52 by use of the hand lever 58, and in order to insure proper clearance between the plate 40 and parts beneath it, if the parts are positioned initially as shown in Fig. 3, the operator swings the hand lever in a clockwise direction, with reference to Fig. 3, the resulting movement of the bar 38 relatively to the arm 52 being limited by engagement of a shoulder 84 on the link 50 with the lower face of the arm. It will be understood that in response to such movement of the bar 38 the arm 36 is swung relatively to the arm 34. It will be evident that by reason of the swinging of the pair of arms 34 and 36 as above described the plate 40 is carried downwardly toward the shoe as it is moved lengthwise of the shoe. The two arms are thus swung to substantially horizontal positions, in which positions they are substantially parallel to each other, the movement of the arm 34 being limited by engagement of a shoulder 86 (Fig. 3) on the bracket 28 with collars 88 (Fig. 2) mounted on the pin 54. A finger 90 fast on the bracket 28 also may serve by engagement with a shoulder 92 on the arm 36 to prevent this arm from swinging too far downwardly.

When the arms 34 and 36 arrive in their substantially horizontal positions the plate 40 is approximately in position for proper engagement with the toe end of the insole. The operator, however, exerts a further pull on the arm 52, as a result of which this arm is moved lengthwise relatively to the arm 34 by reason of the fact that the pin 54 connecting these arms together is mounted in slots 94 in the bifurcated upper end of the arm 34. A spring 96 connected to a clip 98 on the pin 54 and to a pin 100 on the arm 34 serves yieldingly to resist this movement. As a result of the movement of the arm 52 relatively to the arm 34 the pin 54 and the collars 88 thereon are carried into a recess 102 (Fig. 3) provided in a hook-shaped projection 104 on the bracket 28, as illustrated in Fig. 4. This serves to lock the arm 34 against return movement and causes the projection 104 to act as a fixed fulcrum for the arm 52 in the use of this arm as a lever to press the plate 40 down on the work. After the cement on the insole has been properly activated by the heat applied thereto by the plate 40 in the manner illustrated in Fig. 4, the operator begins to advance and close the wipers over the insole by means of the hand lever 16. First, however, by upward movement of the arm 52 he lifts the plate 40 far enough to permit the wipers to move inwardly under it. As he lifts the plate from the insole the operator swings the hand lever 58 in the direction to move the plate outwardly over the wipers, such movement of the plate and of the bar 38 on which it is mounted being permitted by the swinging of the link 42 against the resistance of the spring-pressed pin 46. The plate in this movement spreads the margin of the upper outwardly over the wipers, as illustrated in Fig. 6. Thereafter, while advancing and closing the wipers, the operator presses the plate 40 down on the margin of the upper, so that the plate acts as a retarder to render the wipers more effective in wiping the upper tightly inward over the insole and to prevent any undue wrinkling of the margin. At the same time the margin of the upper is heated by the plate, so that the cement will more effectively adhere thereto. It will be un-

derstood that before the wipers complete their movement the margin of the upper is pulled entirely out from between them and the plate 40 and is wiped down throughout its width upon the cement-coated insole.

By reference particularly to Fig. 2 it will be seen that the mechanism for operating and controlling the plate 40 as above described is, for the most part, offset toward the rear of the machine relatively to a vertical plane extending lengthwise of the shoe midway between the sides of the latter, but that the end portion of the arm 38 which supports the plate is curved laterally of the shoe as well as downwardly, so that the plate intersects this plane and is accordingly positioned by its controlling mechanism in proper relation to the shoe widthwise thereof. The plate has an edge contour corresponding substantially to the edge contour of the toe end of the insole, and its controlling mechanism is so constructed that when the plate is in contact with the insole it lies in substantially parallel relation to the plane of the wipers. Since this mechanism is supported by the cover plate 26 which partakes of any tipping movement of the wipers in adjusting them to the shoe, the relation of the plate 40 to the wipers is not affected by such adjustment. Provision is afforded, however, for tipping movement of the plate laterally of the shoe in response to pressure of the shoe against it, to afford further insurance that it will bear evenly on the cement all around the toe end of the insole. For this purpose a portion of the upper face of the plate is convexly curved laterally of the shoe, as shown at 106 in Fig. 7, and this curved face of the plate engages a complementally curved face on the end of the arm 38. The plate is held on the arm by a pin 108 (Fig. 6) which is mounted for vertical movement in the end of the arm 38 and is provided at its lower end with a circular flange 110 having a convexly curved upper face arranged to be seated in a complementally formed recess 112 (Fig. 8) in the plate. A spring 114 serves by engagement with a collar 116 fast on the pin 108 to urge the pin upwardly and thus to hold the flange 110 in the recess 112. In order to permit the plate 40 to be readily detached from the arm 38 the plate is provided with a slot 118 extending from one edge thereof to the pin 108 and through which the pin extends, the slot being wider than the pin so as to permit the plate to tip as above described. The operator may press the pin downwardly to release the plate and may then readily slide the plate out from under the end of the arm. In the construction shown the plate 40 has a serrated lower face to render it more quickly effective in softening the cement through the action of the heat applied thereto.

After the plate 40 has been used in the manner previously described it is returned to its initial position on the heater 74. It will be evident that when permitted by the operator the spring 96 serves to withdraw the pin 54 and the collars 88 thereon from the recess 102 in the hook-shaped projection 104, and that the spring 70 by its action on the arm 34 serves thereafter to return this arm and the parts connected therewith to their starting positions. The operator naturally lifts the plate 40 somewhat away from the shoe and the wipers by means of the handle 60 after the wiping operation, but he need not continue to control the parts by this handle until they are returned to their starting positions, since the hook-shaped projection 104 is provided with an 75

inclined face 120 (Fig. 3) arranged to engage the portion of the link 62 adjacent to the pin 64 and thus to guide the bar 38 in its movement under the influence of the spring 70 so that the plate 40 will be returned properly to its position on top of the heater 74.

Having described the invention, what I claim as new and desire to secure by Letters Patent of the United States is:

- 10 1. In a lasting machine, the combination with a shoe support and lasting means, of a member for applying heat to the portion of the shoe operated upon by said lasting means, a heater for heating said member, and movably mounted mechanism arranged to support said member and movable to carry the member away from the heater to a position opposite the bottom of the shoe and also to carry it heightwise of the shoe into contact therewith.
- 15 2. In a lasting machine, the combination with a shoe support and lasting means, of a member for applying heat to the portion of the shoe operated upon by said lasting means, a heater on which said member rests in an idle position, and movably mounted mechanism arranged to support said member and movable by the operator to lift the member from the heater and to carry it to a position over the shoe and also to carry it downwardly into contact with the shoe.
- 20 3. In a lasting machine, the combination with a shoe support and lasting means, of a member for applying heat to the portion of the shoe operated upon by said lasting means, a heater on which said member rests in an idle position, and movably mounted mechanism arranged to support said member and movable by the operator to carry the member away from the heater to a position opposite the bottom of the shoe and also to carry it heightwise of the shoe into contact therewith, and a spring for operating said mechanism to impart return movement to said member.
- 25 4. In a lasting machine, the combination with a shoe support and lasting means, of a member for applying heat to the portion of the shoe operated upon by said lasting means, an arm arranged to support said member and to be swung heightwise of the shoe to press the member on the shoe, and another arm supporting said first-named arm and extending normally heightwise of the shoe, said other arm being mounted for swinging movement to permit said member to be carried by the first arm from an initial retracted position to a position opposite the bottom of the shoe.
- 30 5. In a lasting machine, the combination with a shoe support and lasting means, of a member for applying heat to the portion of the shoe operated upon by said lasting means, an arm arranged to support said member and to be swung heightwise of the shoe by the operator to press the member on the shoe, another arm supporting said first-named arm and extending normally heightwise of the shoe, said other arm being mounted for swinging movement toward the shoe to permit said member to be carried by the first arm from an initial retracted position to a position opposite the bottom of the shoe, and means for locking said other arm against return movement while the operator swings said first arm to press said member on the shoe.
- 35 6. In a lasting machine, the combination with a shoe support and lasting means, of a member for applying heat to the portion of the shoe operated upon by said lasting means, an arm arranged to support said member and to be swung heightwise of the shoe by the operator to press the member on the shoe, another arm supporting said first-named arm and extending normally heightwise of the shoe, said other arm being mounted for swinging movement toward the shoe to permit said member to be carried by the first arm from an initial retracted position to a position opposite the bottom of the shoe, another arm connected to said bar and mounted on one of said pair of arms for swinging movement heightwise of the shoe to press said member on the shoe by swinging the bar relatively to the pair of arms, a handle by which the operator thus moves said other arm, and mechanism con-
- 40 7. In a lasting machine, the combination with a shoe support and lasting means, of a member for applying heat to the portion of the shoe operated upon by said lasting means, a bar for supporting said member, a pair of arms located respectively at different distances from the shoe and arranged to extend normally heightwise of the shoe for controlling said bar, said arms being mounted for swinging movements toward the shoe to permit said member to be carried by the bar from an initial retracted position to a position opposite the bottom of the shoe, and another arm connected to said bar and mounted on one of said pair of arms for swinging movement heightwise of the shoe to press said member on the shoe by swinging the bar relatively to the pair of arms.
- 45 8. In a lasting machine, the combination with a shoe support and lasting means, of a member for applying heat to the portion of the shoe operated upon by said lasting means, an arm arranged to support said member and movable by the operator to carry the member from an initial retracted position to a position opposite the bottom of the shoe, a handle by which the operator thus moves said arm, and mechanism controlled by said handle for moving said member relatively to the arm to position it in proper relation to the shoe.
- 50 9. In a lasting machine, the combination with a shoe support and lasting means, of a member for applying heat to the portion of the shoe operated upon by said lasting means, an arm arranged to support said member and movable lengthwise by the operator to carry the member from an initial retracted position to a position opposite the bottom of the shoe, a hand lever mounted on said arm and movable bodily to impart the lengthwise movement to the arm, and means connecting the hand lever to said member for moving the member lengthwise of the arm by swinging the hand lever relatively to the arm.
- 55 10. In a lasting machine, the combination with a shoe support and lasting means, of a member for applying heat to the portion of the shoe operated upon by said lasting means, a bar for supporting said member, a pair of arms located respectively at different distances from the shoe and arranged to extend normally heightwise of the shoe for controlling said bar, said arms being mounted for swinging movements toward the shoe to permit said member to be carried by the bar from an initial retracted position to a position opposite the bottom of the shoe, another arm connected to said bar and mounted on one of said pair of arms for swinging movement heightwise of the shoe to press said member on the shoe by swinging the bar relatively to the pair of arms, a handle by which the operator thus moves said other arm, and mechanism con-

- nected to said bar and controlled by said handle for moving the bar lengthwise relatively to said other arm.
11. In a lasting machine, the combination with 5 means for supporting a last having an upper and an insole thereon, and means for laying the margin of the upper inwardly over the insole to cause it to be secured to the insole by cement previously applied to the insole, of a member for 10 heating the cement before the margin of the upper is thus laid inwardly over the insole, and movably mounted means for carrying said member into contact with the cement on the insole and for also positioning it in contact with the 15 margin of the upper for heating and controlling said margin as it is laid inwardly over the insole.
12. In a lasting machine, the combination with means for supporting a last having an upper and an insole thereon, and wipers for wiping the 20 margin of the toe end of the upper inwardly over the insole to cause it to be secured to the insole by cement previously applied to the insole, of a member for heating the cement before the margin of the upper is thus wiped inwardly over the 25 insole, and movably mounted means for carrying said member into contact with the cement on the insole and for thereafter retracting it from the insole and positioning it in contact with the margin of the upper outturned over the wipers 30 for heating and controlling said margin as it is wiped inwardly by the wipers.
13. In a lasting machine, the combination with means for supporting a last having an upper and an insole thereon, and means for laying the 35 margin of the upper inwardly over the insole to cause it to be secured to the insole by cement previously applied to the insole, of a member for applying heat to the cement before the margin of the upper is thus laid inwardly over the insole, heating means, and movably mounted mechanism for carrying said member away from the heating means and into contact with the cement on the insole and for thereafter returning it into 40 position to be heated by said heating means.
14. In a lasting machine, the combination with 45 means for supporting a last having an upper and an insole thereon, and means for laying the margin of the upper inwardly over the insole to cause it to be secured to the insole by cement previously applied to the insole, of a member for applying heat to the cement before the margin of the upper is thus laid inwardly over the insole, means for heating said member, mechanism movable by the operator to carry said member away 50 from the heating means and into contact with the cement on the insole, and spring means for imparting return movement to said mechanism.
15. In a lasting machine, the combination with 55 means for supporting a last having an upper and an insole thereon, and means for laying the margin of an end of the upper inwardly over the insole to cause it to be secured to the insole by cement previously applied to the insole, of a member for applying heat to the cement before 60 the margin of the upper is thus laid inwardly over the insole, a heater, and movably mounted means for carrying said member away from the heater lengthwise and heightwise of the shoe into contact with the cement on the insole and for thereafter returning it into contact with the heater.
16. In a lasting machine, the combination with 65 means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to be 70 swung heightwise of the shoe by the operator to 75
- inwardly over the insole to cause it to be secured to the insole by cement previously applied to the insole, of a member for applying heat to the cement before the margin of the upper is thus laid inwardly over the insole, mechanism connected to said member for controlling it, a heater on which the member rests in an idle position, a handle on said mechanism to enable the operator to lift the member and move it lengthwise and heightwise of the shoe into contact with the cement on the insole, and a spring for operating said mechanism to impart return movement lengthwise of the shoe to said member.
17. In a lasting machine, the combination with 10 means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, a heater on which 15 said member rests in an idle position, an arm connected to said member and arranged to be swung heightwise of the shoe by the operator to 20 press the member on the insole, and another arm arranged to support said first-named arm and mounted to swing lengthwise of the shoe to permit said member to be carried by the first arm from over the heater to a position over the insole.
18. In a lasting machine, the combination with 25 means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to be swung heightwise of the shoe by the operator to 30 press the member on the insole, another arm pivotally supporting said first-named arm and arranged to swing lengthwise of the shoe in response to a pull of the first arm thereon to permit said member to be carried by the first arm to a position over the insole, and a spring for imparting return movement to said other arm.
19. In a lasting machine, the combination with 35 means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to be 40 swung heightwise of the shoe by the operator to press the member down on the insole, and another arm pivotally supporting said first-named arm and mounted to swing lengthwise of the shoe in a downward direction in response to a pull of the first arm thereon.
20. In a lasting machine, the combination with 45 means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to be 50 swung heightwise of the shoe by the operator to 55

press the member down on the insole, another arm pivotally supporting said first-named arm and mounted to swing lengthwise of the shoe in a downward direction in response to a pull of the first arm thereon, and means for locking said other arm against return movement while the operator presses said member down on the insole by swinging movement of said first arm.

21. In a lasting machine, the combination with means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to be swung heightwise of the shoe by the operator to press the member down on the insole, another arm arranged to support said first-named arm and mounted to swing lengthwise of the shoe in a downward direction in response to a pull of the first arm thereon, a pivotal connection between said arms, and a device into operative relation to which said pivotal connection is movable by a lengthwise movement of said first arm relatively to the other arm to provide a fixed fulcrum for said first arm as the latter is swung to press said member on the insole.

22. In a lasting machine, the combination with means for supporting a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, a bar supporting said member and arranged to extend lengthwise of the shoe, a pair of arms spaced apart lengthwise of the shoe for controlling said bar, said arms being mounted for swinging movements lengthwise of the shoe to permit said member to be carried by the bar from an initial retracted position to a position opposite the end of the insole, and another arm connected to said bar and mounted on one of said pair of arms for swinging movement heightwise of the shoe to press said member on the insole by swinging the bar relatively to the pair of arms.

23. In a lasting machine, the combination with means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, a bar supporting said member and arranged to extend lengthwise of the shoe, a pair of arms spaced apart lengthwise of the shoe for controlling said bar, said arms being mounted for swinging movements lengthwise of the shoe in downward directions to permit said member to be carried by the bar from an initial retracted position to a position over the insole, a connection between one end of said bar and one of said pair of arms, a third arm mounted on the other of said pair of arms for swinging movements heightwise of the shoe, and a link connection between said third arm and the bar for swinging the bar downwardly to press said member

on the insole by downward movement of said third arm.

24. In a lasting machine, the combination with means for supporting a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm arranged to support said member and movable by the operator to carry the member from an initial retracted position to a position opposite the end of the insole, and mechanism under control of the operator as he thus moves said arm for moving the member relatively to the arm in directions lengthwise of the shoe.

25. In a lasting machine, the combination with means for supporting a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to be swung heightwise of the shoe by the operator to press the member on the insole, a support for said arm movable lengthwise of the shoe to permit said member to be carried by the arm from an initial retracted position to a position opposite the end of the insole, and mechanism under control of the operator during the movements of the arm for moving said member lengthwise of the shoe relatively to the arm.

26. In a lasting machine, the combination with means for supporting a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, an arm connected to said member and arranged to extend lengthwise of the shoe and to be swung heightwise of the shoe by the operator to press the member on the insole, a support for said arm movable lengthwise of the shoe to permit said member to be carried by the arm from an initial retracted position to a position opposite the end of the insole, a hand lever pivotally mounted on said arm and movable bodily to impart to the arm lengthwise movement and swinging movement, and means connecting the hand lever to said member for moving the member lengthwise of the shoe relatively to said arm by swinging movement of the hand lever.

27. In a lasting machine, the combination with means for supporting a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, a bar supporting said member and arranged to extend lengthwise of the shoe, a pair of arms spaced apart lengthwise of the shoe for controlling said bar, said arms being mounted for swinging movements lengthwise of the shoe to permit said member to be carried by the bar from an initial retracted position to a

position opposite the end of the insole, another arm connected to said bar and mounted on one of said pair of arms for swinging movement heightwise of the shoe to press said member on the insole by swinging the bar relatively to the pair of arms, and mechanism on said other arm connected to said bar for moving the bar lengthwise of the shoe relatively to the several arms.

5 28. In a lasting machine, the combination with means for supporting bottom upward a last having an upper and an insole thereon, and means for laying the margin of an end of the upper inwardly over the insole to cause it to be secured to the insole by cement previously applied to the insole, of a member for applying heat to the cement before the margin of the upper is thus laid inwardly over the insole, a bar supporting said member and arranged to extend lengthwise of the shoe, a pair of arms spaced apart lengthwise of the shoe for controlling said bar, said arms being mounted for swinging movements lengthwise of the shoe in downward directions to permit said member to be carried by the bar from an initial retracted position to a position over the insole, a link connection between one end of said bar and one of said pair of arms, a third arm mounted on the other of said pair of arms for swinging movements heightwise of the shoe, a link connection between said third arm and the bar for swinging the bar downwardly to press said member on the insole by downward movement of said third arm, and a hand lever on said third arm connected to the bar for moving the bar lengthwise of the shoe relatively to the several arms.

29. In a lasting machine, the combination with means for supporting a last having an upper and an insole thereon, and wipers for wiping the margin of an end of the upper inwardly over the insole, of a retarder for pressing the margin of the upper against the wipers to control said margin in the lasting operation, an arm arranged to support said retarder and to be swung heightwise of the shoe by the operator to press the retarder on the work, another arm supporting said first-named arm and mounted to swing lengthwise of the shoe in response to a pull of the first arm thereon to permit the retarder to be moved by the first arm lengthwise of the shoe relatively to the wipers from an initial retracted position, and a spring against the resistance of which said other arm is thus movable.

30. In a lasting machine, the combination with means for supporting a last having an upper and an insole thereon, and wipers for wiping the margin of an end of the upper inwardly over the insole, of a retarder for pressing the margin of the upper against the wipers to control said margin in the lasting operation, an arm arranged to support said retarder and to be swung heightwise of the shoe by the operator to press the retarder on the work, another arm supporting said first-named arm and mounted to swing lengthwise of the shoe to permit the retarder to be moved by the first arm lengthwise of the shoe relatively to the wipers from an initial retracted position, and means for locking said other arm against return movement while the operator holds the retarder in operative position by said first arm.

31. In a lasting machine, the combination with means for supporting bottom upward a last having an upper and an insole thereon, and wipers for wiping the margin of an end of the upper

inwardly over the insole, of a retarder for pressing the margin of the upper against the wipers to control said margin in the lasting operation, an arm arranged to support said retarder and to be swung heightwise of the shoe by the operator to press the retarder down on the work, another arm supporting said first-named arm and mounted to swing lengthwise of the shoe in a downward direction to permit the retarder to be moved lengthwise of the shoe relatively to the wipers from an initial retracted position, a spring tending to impart return movement to said other arm, and means for locking said other arm against return movement while the operator presses the retarder downwardly by the first arm.

32. In a lasting machine, the combination with means for supporting bottom upward a last having an upper and an insole thereon, and wipers for wiping the margin of an end of the upper inwardly over the insole, of a retarder for pressing the margin of the upper against the wipers to control said margin in the lasting operation, an arm arranged to support said retarder and to be swung heightwise of the shoe by the operator to press the retarder down on the work, another arm supporting said first-named arm and mounted to swing lengthwise of the shoe in a downward direction in response to a pull of the first arm thereon to permit the retarder to be moved lengthwise of the shoe from an initial retracted position, a pivotal connection between said arms, and a device into operative relation to which said pivotal connection is movable by a lengthwise movement of said first arm relatively to the other arm to provide a fixed fulcrum for said first arm in its use by the operator to press the retarder downwardly.

33. In a lasting machine, the combination with means for supporting bottom upward a last having an upper and an insole thereon, and wipers for wiping the margin of an end of the upper inwardly over the insole, of a retarder for pressing the margin of the upper against the wipers to control said margin in the lasting operation, an arm arranged to support said retarder and to be swung heightwise of the shoe by the operator to press the retarder down on the work, another arm supporting said first-named arm and mounted to swing lengthwise of the shoe in a downward direction in response to a pull of the first arm thereon to permit the retarder to be moved lengthwise of the shoe from an initial retracted position, a pin pivotally connecting said arms together and movable lengthwise of said other arm by a pull applied to the first arm, a member under which the pin is thus moved to provide a fixed fulcrum for said first arm in its use to press the retarder downwardly, and a spring for yieldingly resisting such movement of the pin.

34. In a lasting machine, the combination with means for supporting bottom upward a last having an upper and an insole thereon, and wipers for wiping the margin of an end of the upper inwardly over the insole, of a retarder for pressing the margin of the upper against the wipers to control said margin in the lasting operation, a bar supporting said retarder and arranged to extend lengthwise of the shoe, a pair of arms spaced apart lengthwise of the shoe for controlling said bar, said arms being mounted for swinging movements lengthwise of the shoe in downward directions to permit the retarder to be carried by the bar from an initial retracted position toward operative position, and another arm connected to

said bar and mounted on one of said pair of arms for swinging movement heightwise of the shoe to press the retarder downwardly on the work by swinging said bar relatively to the pair of arms.

35. In a lasting machine, the combination with means for supporting bottom upward a last having an upper and an insole thereon, and wipers for wiping the margin of an end of the upper inwardly over the insole, of a retarder for pressing the margin of the upper against the wipers to control said margin in the lasting operation, a bar supporting said retarder and arranged to extend lengthwise of the shoe, a pair of arms spaced apart lengthwise of the shoe for controlling said bar, said arms being mounted for swinging movements lengthwise of the shoe in downward directions to permit the retarder to be carried by the bar from an initial retracted position toward operative position, a link connecting one end of said bar to one of the pair of arms, a third arm mounted on the other of said pair of arms for swinging movements heightwise of the shoe, and a link connecting said third arm to the bar for swinging the bar downwardly by downward movement of said third arm.

36. In a lasting machine, the combination with means for supporting a last having an upper and an insole thereon, and wipers for wiping the margin of an end of the upper inwardly over the insole, of a retarder for pressing the margin of the upper against the wipers to control said margin in the lasting operation, a member arranged to support said retarder and movable lengthwise of the shoe to carry the retarder from an initial retracted position toward operative position, a handle by which the operator thus moves said member, and mechanism controlled by said handle for moving the retarder in directions lengthwise of the shoe relatively to said member.

37. In a lasting machine, the combination with means for supporting a last having an upper and

an insole thereon, and wipers for wiping the margin of an end of the upper inwardly over the insole, of a retarder for pressing the margin of the upper against the wipers to control said margin in the lasting operation, an arm arranged to extend lengthwise of the shoe and to support said retarder, said arm being movable lengthwise to carry the retarder from an initial retracted position toward operative position and being also mounted for swinging movement heightwise of the shoe to press the retarder on the work, a hand lever mounted on said arm and movable bodily thus to operate the arm, and mechanism for moving the retarder lengthwise of the shoe relatively to said arm by swinging movement of the hand lever.

38. In a lasting machine, the combination with means for supporting bottom upward a last having an upper and an insole thereon, and wipers for wiping the margin of an end of the upper inwardly over the insole, of a retarder for pressing the margin of the upper against the wipers to control said margin in the lasting operation, a bar supporting said retarder and arranged to extend lengthwise of the shoe, a pair of arms spaced apart lengthwise of the shoe for supporting said bar, said arms being mounted for swinging movements lengthwise of the shoe in downward directions to permit the retarder to be carried by the bar from an initial retracted position toward operative position, a link connection between one end of the bar and one of said arms to permit lengthwise movement of the bar relatively to that arm, a third arm mounted on the other of said pair of arms for swinging movement heightwise of the shoe, a link connection between said third arm and the bar, a member on said third arm for operating it, and means connecting said member to the bar for moving the bar lengthwise relatively to the several arms.

RENÉ E. DUPLESSIS.
